UNITED STATES PATENT OFFICE

100,393

DESIGN FOR A TALC BOTTLE OR SIMILAR ARTICLE

Joseph S. Stein, Chicago, Ill., assignor to Lucien Lelong Inc., Chicago, Ill., a corporation of Illinois

Application May 2, 1936, Serial No. 62,430

Term of patent 3½ years

To all whom it may concern:

Be it known that I, Joseph S. Stein, a citizen of the United States, and a resident of the city of Chicago, county of Cook, and State of Illinois, have invented a new, original, and ornamental Design for a Talc Bottle or Similar Article, of which the following is a specification, reference being had to the accompanying drawing, forming a part thereof.

On the drawing:

Figure 1 is a front elevational view of the talc
bottle showing my new design.

Figure 2 is a rear elevational view thereof.

Figures 3 and 4 are side elevational views, and Figure 5 is a top plan view thereof.

I claim:

The ornamental design for a talc bottle or a similar article as shown.

JOSEPH S. STEIN.
